UNITED STATES PATENT OFFICE.

FRANK W. BUTTERWORTH, OF DANVILLE, ILLINOIS, ASSIGNOR TO WESTERN BRICK COMPANY, OF DANVILLE, ILLINOIS, A CORPORATION OF ILLINOIS.

METHOD OF FORMING TEXTURE BRICK.

Application filed October 27, 1921. Serial No. 510,837.

To all whom it may concern:

Be it known that I, FRANK W. BUTTERWORTH, a citizen of the United States, residing at Danville, in the county of Vermilion and State of Illinois, have invented certain new and useful Improvements in Methods of Forming Texture Brick, of which the following is a specification.

This invention relates to a new and improved method of forming texture bricks and more particularly to a method of forming such bricks having a sanded surface.

Both for ease in handling and for securing a better appearance, it is highly desirable that the brick have a sanded surface. A sanded surface improves and softens the color and eliminates all of the high lights and polished surfaces. A film of sand upon the surface also prevents the green brick from sticking together on the dry-house cars, and further prevents them from sticking together in the kilns.

Various methods have been used for forming a texture surface upon face brick but, in so far as I am aware, it has not been heretofore deemed practical to sand the surface of such bricks. Sanding the surface would lose most of its utility if the entire surface is thereafter disturbed in forming the texture effect.

It is an object of the present invention to provide a new and improved method of forming texture bricks having a sanded surface.

It is a further object to provide such a method wherein the surface is sanded prior to the formation of the texture therein, this formation of the texture not working the entire surface and permitting the sand to remain upon much of the surface.

It is an additional object to provide a method of this character which does not require any additional handling or working of the brick or brick-forming material other than that now required in the formation of preferred types of texture brick.

It is also an object to provide a method which is readily accomplished by automatic machinery.

Other and further objects will appear as the description proceeds.

Broadly, my invention comprises the extrusion of a brick forming ribbon from dies or the formation of such a ribbon in any usual manner and the sanding of the ribbon.

It further involves the stippling or marking of the surface to form a texture brick, this stippling or marking, however, permitting much of the surface to remain undisturbed. The sand is retained upon the undisturbed surface. In its preferable form, this stippling is accomplished by means of resilient fingers moved into and out of engagement with the surface of the brick ribbon.

I have described in my copending application, Serial No. 449,439, filed March 3, 1921, a method of coloring the surfaces of bricks. In that method the coloring matter is worked into the surface of the brick, while the sand in the present case merely adheres to the undeformed portions of the brick surface.

For accomplishing this stippling or marking of the surface of the ribbon, I have found the machine covered by the joint patent to myself and G. Holmes, for Brickmaking machine, Patent No. 1,191,925, granted July 18, 1916, to be particularly efficient. I have shown this machine in the accompanying drawings in order to illustrate the application of my method, but it is to be understood that this machine in itself forms no part of the present invention, and is only one apparatus capable of performing my invention.

I have illustrated certain preferred apparatus for carrying out my method in the accompanying drawings, in which—

Figure 1 is a plan view of the apparatus; and

Figure 2 is an end elevation thereof.

As shown in the drawings, the machine consists in the conveyor 5 adapted to carry the ribbon of brick-forming material away from the die 6 from which it is extruded. The hardened surface layers of the ribbon are cut away by the wires 8 and the particles of material cut by these wires are removed from the ribbon by the plow-shaped member 9. The movable member 10 is carried above the ribbon and is provided with a large number of resilient steel bristles or fingers 11. This member 10 is provided with a housing 11 adapted to receive an eccentric carried by the shaft 12. The shaft 12 is driven by pulley 13 and is carried by the side members 14 which are connected by the cross members 15 to form a rectangular frame. This frame is supported upon col-

umns 16 each of which carries at its upper end a fixed journal 17 through which an adjusting screw 18 is passed. This screw carries a movable adjusting block 19 which bears against the lower face of the frame formed by the members 14 and 15, so that the frame may be raised or lowered to vary the action upon the material.

The two ends of the member 10 are pivotally connected to the bell crank levers 20, which levers are pivoted upon the shafts 21. The upper arms of these two levers are connected by the rod 22. This construction assures a proper relative movement of the 15 two ends of the member 10.

A similar pair of members 23 is located adjacent the sides of the ribbon of brick-forming material and is operated by the pulley 24 upon the shaft 25.

20 The sand distributing means 26 is supported from a cross frame member 15 by straps 27. This member 26 is provided with the screen bottom 28 through which the sand falls upon the ribbon of brick-forming material. The side faces of the brick ribbon are sanded by means of a hopper 29 as shown at the right of Figure 1. This hopper has the peaked bottom 30 adapted to distribute sand to screens 31 located above either side 25 of the ribbon. The blowers 32 are provided to force the falling streams of sand against the sides of the ribbon.

In the operation of the machine, the ribbon of brick-forming material is extruded 35 from the dies 6, is trimmed by the wires 8 and cleaned by the plow 9. Sand is then dropped on the ribbon of material and as the ribbon passes under the member 10 with its fingers 11, this member 10 moves toward 40 and away from the ribbon and also longitudinally in the direction taken by the ribbon, the member being actuated by the eccentric cam rotated by pulley 13. These spring fingers or bristles engage the surface 45 of the material and stipple that surface, and form it with a plurality of short lines. Due to the resilience of the fingers or bristles they are bent as they engage the ribbon and as they move away from the ribbon in 50 the actuation of the member 10, their resilience causes them to straighten and in so doing they pick small particles from the surface of material.

The sides of the ribbon have sand blown 55 thereon with sufficient force so that the sand adheres to the damp surface. This surface is worked by the operation of the bristles upon the members 23 in a manner similar to the working of the top surface. It is to be understood that this working is not such as to roughen the entire surface of the material. The stippling has smooth, unworked spaces 60 between the markings and these spaces retain the sand.

While I have shown one preferred form 65 of apparatus for stippling the sanded ribbon, it is to be understood that this may be done by other forms of apparatus, the essential feature of the invention being the application of sand to the surface, thereafter 70 working or stippling the surface while permitting the said to remain upon the untouched portion of the surface. I therefore contemplate such variations and modifications as are covered by the spirit and scope 75 of the appended claims.

I claim:

1. The method of forming texture bricks comprising applying sand to the surface thereof and thereafter stippling said surface. 80

2. The method of forming texture bricks comprising applying sand to the surface thereof and thereafter stippling said surface by means of a plurality of fingers moved into and out of engagement with 85 the surface.

3. The method of forming texture bricks comprising applying sand to the surface thereof and thereafter stippling said surface by means of a plurality of resilient 90 fingers.

4. The method of forming texture bricks comprising applying sand to the surface thereof and thereafter forming in said surface a plurality of spaced markings, the sand remaining upon the surface between 95 the markings.

5. The method of forming texture bricks comprising forming a ribbon of brick material, sanding the surface thereof, imparting a linear movement to the ribbon, and stippling the surface by means of a plurality of fingers moved into and out of engagement with the ribbon, and thereafter cutting the ribbon into bricks. 100

6. The method of forming texture bricks comprising forming a ribbon of brick material, sanding the surface thereof, imparting a linear movement to the ribbon, and stippling the surface by means of a plurality of fingers moved into and out of engagement with the ribbon, the fingers having a different rate of movement from that of the ribbon, and thereafter cutting the ribbon into bricks. 110

7. The method of forming texture bricks comprising forming a ribbon of brick material, sanding the surface thereof, imparting a linear movement to the ribbon, and stippling the surface by means of a plurality of fingers moved into and out of engagement with the ribbon, the fingers being resilient and tending to be distorted upon engagement with the ribbon, and thereafter cutting the ribbon into bricks. 115

8. The method of forming texture bricks comprising applying sand to moist surfaces of the brick, the sand adhering thereto, and 120

thereafter stippling said surface, said stippling leaving portions of the sanded surface undisturbed.

9. The method of forming texture bricks comprising forming a ribbon of brick material, applying sand loosely to the moist surface of the ribbon, imparting a linear movement to the ribbon, and stippling the surface by means of a plurality of fingers moved

into and out of engagement with the ribbon, the fingers being resilient and tending to be distorted by engagement with the ribbon, portions of the ribbon surface remaining undeformed, and thereafter cutting the ribbons into bricks.

Signed at Danville, Illinois, this 14th day of October, 1921.

FRANK W. BUTTERWORTH.
